UNITED STATES PATENT OFFICE.

WILLIAM P. QUENTELL, OF NEW YORK, N. Y.

ADDING-MACHINE.

SPECIFICATION forming part of Letters Patent No. 756,706, dated April 5, 1904.

Application filed December 22, 1903. Serial No. 186,212. (No model.)

To all whom it may concern:

Be it known that I, WILLIAM P. QUENTELL, a citizen of the United States, residing at New York city, in the county of New York and State of New York, have invented new and useful Improvements in Adding-Machines, of which the following is a specification.

This invention relates to adding-machines; and the invention resides in novel features of construction set forth in the following specification and claims and illustrate in the annexed drawings, in which—

Figure 1 is a plan view of a machine embodying this invention. Fig. 2 is a section along $\alpha\alpha$, Fig. 1. Fig. 3 is an inverted plan view of Fig. 1. Fig. 4 is a section along $y\gamma$, Fig. 1. Fig. 5 shows a form of stylus. Fig. 6 is a plan view of a portion of a disk on a larger scale than the preceding figures. Fig. 7 is a section along $z\zeta$, Fig. 6. Fig. 8 is a section along $z'\zeta'$, Fig. 6.

The machine comprises a number-disk a , which carries numbers up to any desired denomination. The figures from "0" to "99" have been found to be a practical arrangement. A frame or support is shown at b . This support can be of any suitable shape or construction, such as box or open-work. A plate, as shown in the drawings, will answer. The buttons or legs c for the supporting-plate when made of rubber will not be apt to slip when the device is manipulated. This frame b has a sight-opening at d , through which one or another of the figures of disk a is exposed as the latter rotates. The pivot e of the rotary disk is supported by a strip or bridge-piece f . The opening g in the frame b has lip or part g' , forming a zero-stop, as presently explained. The disk a is partly exposed through this opening g . The disk has a perforation or seat at h for the insertion of a stylus or like instrument, Fig. 5, by which the disk can be rotated or set to zero. When the stylus is arrested by stop g' , the figure "0" shows at sight d . About the circumferential portion of disk a are holes or catches i . The frame or support has a slot at k . This slot is shown running along or exposing a number of said holes i . The holes shown are a cheap construction;

but other means, such as corrugations or shoulders or other catch portions for a stylus to take hold, can be employed.

Guides m are shown leading into slot k . These guides might be called "branch" slots of the trunk or main slot k . These guides are shown numbered from "1" to "9." For spacing and convenience of selection the odd-numbered guides can be placed on one side of the slot and the even numbers on the opposite side. The guide numbered "9," for example, is at such distance from the stopping-point of the slot—that is, the end of the slot just past guide "1"—that when a stylus or the like is inserted into the hole i at such guide "9" and the disk is rotated, as shown by the arrow, by moving the stylus to rotate the disk until the stylus is stopped at such stopping end of the slot such disk has advanced nine numbers—that is, the number now showing through the sight d is nine higher than the number last preceding at the sight. Similarly by starting at another guide, as "8" or "5," the disk is rotated or advanced a corresponding number in each case.

The stylus can be a rod of metal or a pencil, or other instruments might be made to answer.

The guides m are of such size or enlarged at their ends that the stylus can be readily inserted therein and then run along to slot k to engage into the required seat or hole i . As these holes are small and close together, mistakes are liable to occur when inserting the stylus into these holes direct; but errors can be easily avoided by previously inserting the stylus in a guide.

In addition to guides k the disk may have guides or grooves o branching from holes i , so that a stylus will be guided both by guide m and by groove or channel-guide o to enter the required one of the holes i . The guides or grooves o are readily formed by depressions in the top or face of the disk, giving the under side or face of the disk a wavy or corrugated appearance. The sheet metal forming the disk is sufficiently thin or flexible to allow this deflection or corrugation.

The under side of disk a is held from bend-

ing or supported at an edge portion by a plate *n*, having an offset or portion which while allowing the entry of the stylus into a hole *i* a certain distance at the same time suitably limits such insertions.

A stop or under plate *p* at perforation *h* limits the entry of the stylus at this point, so that when rotating the disk to the zero-stop the stylus cannot project and strike the bridge *f*, whereby mistakes or premature stoppage might be caused.

A counter is shown at *q* in form of a hand pointing to a series of figures or a dial—say “0” to “7.” In the example shown this counter is a hundreds-counter. If, for example, the disk should show a figure, say “80,” at the sight *d* and the hand *q* point to “2,” a total of “280” would be thus indicated.

The hand *q* is connected to a gear or segment *r* by pivot *s*, which is a shoulder-screw. A spring *t* gives a friction to prevent accidental shift or rotation of the hand. A pin *u* connects the hand and gear, so that they swing together. This pin *u* projects into a slot in plate *b*, whereby its movement or swing can be limited between certain points—for example, “0” and “7” in the example shown. In moving its figure “99” along past sight *d* plate *a* by tooth *v* moves gear *r* one step to set the hand *q* along one figure. When the disk *a* is set to zero, the tooth *v* is in such position that the gear *r* can be moved back to zero, which is done by the operator moving hand *q* to zero.

35 Suppose three columns of figures are to be added up. The first or right-hand column or units are first added by successively inserting the stylus into the guides respectively corresponding to the successive figures in the column and rotating the disk the required or corresponding extent by moving the stylus each time to the lower terminal of the slot. If such first or unit column should add up to “103,” the hundreds-counter stands at “1” and the disk shows the figure “3” at sight *d*. The figure “3” is then noted or put down by pencil or the like with a memorandum of ten to carry. The disk and counter are then both set to zero. To the next column is then first 40 added the amount carried, say ten, which is made to appear at sight *d* by moving plate *a* by successively actuating from guide “9” and guide “1.” Then the figures in said next column are successively noted. Suppose the total 45 of the second column is “48.” Such sum will now appear at sight *d*. Putting down the “8” leaves four to carry to the third column. The parts *a* and *q* are then again set to zero. Noting the next or third column of figures 50 plus four, or the amount carried—giving, for example, “56”—the grand total will be “5683.”

A stylus 11 is shown with a cap or pencil engaging part to be adapted for application to

a pencil; but the invention is not limited to any special form of stylus.

What I claim, and desire to secure by Letters Patent of the United States, is—

1. An adding-machine, comprising a number-disk having a plurality of openings, a plate over the disk and having a slot and guides leading to the slot to facilitate access to the openings. 70

2. An adding-machine, comprising a number-disk having openings between its periphery and axis, a plate over the disk having a slot and guides leading to the slot to facilitate access to the openings. 75

3. An adding-machine, comprising a number-disk having openings between its periphery and axis, a plate over the disk and having segment-shaped slot and guides leading to the slot to facilitate access to the openings. 80

4. A number-disk with holes or catches and a frame or support with a slot and guides, said 85 guides having enlargements for ready entrance or insertion of a stylus or the like.

5. An adding-machine comprising a number-disk having a plurality of openings between its periphery and axis, a plate over the 90 disk and having a segment-shaped slot provided with branches to permit of access to the openings.

6. An adding-machine, comprising a number-disk having openings between its periphery and axis, a plate over the disk and having a slot provided with branches extending in opposite directions to permit of access to the 95 openings.

7. An adding-machine comprising a perforated number-disk, guides leading to the perforation and a frame or support. 100

8. An adding-machine comprising a perforated number-disk having channels for guiding a stylus or the like to the holes and a frame 105 or support having a slot corresponding to the perforations.

9. An adding-machine, comprising a number-disk having openings between its periphery and axis, a plate over the disk and having a slot provided with branches extending in opposite directions and the said plate being provided with an inwardly-projecting finger 110 made to act as a stop.

10. An adding-machine, comprising a number-disk, a plurality of guides between its periphery and axis and having openings, a frame having a slot with a series of branches leading into opposite directions therefrom, and means carried by the frame for supporting the disk. 115

11. A number-disk combined with a counter comprising a gear, a hand, a shoulder-screw and friction means, said screw being made to connect the hand and gear and to hold the 120 friction under tension.

12. A number-disk combined with a gear actuated thereby, a hand, and a pivot and pin

for connecting the hand and gear to make them move in unison.

13. An adding-machine, comprising a frame having a slot, a rotary number-disk supported 5 below the frame, said disk being provided with a plurality of guides annularly arranged and having openings, a counter being provided with a segment and means carried by the disk for engagement with the segment for actuating the counter.

14. An adding-machine, comprising a suitable support including a plate having a slot

with branches, a rotary number-disk carried thereby, said disk being provided with a series of recesses having holes for receiving a stylus, 15 and means connected with the support for limiting the depth of insertion of the stylus.

In testimony whereof I have hereunto set my hand in the presence of two subscribing witnesses.

WILLIAM P. QUENTELL.
